UNITED STATES PATENT OFFICE.

CHARLES M. KIMBALL, OF TOLEDO, OHIO.

BOTTLE OR EGG CARRIER.

SPECIFICATION forming part of Letters Patent No. 537,043, dated April 9, 1895.

Application filed July 9, 1894. Serial No. 516,927. (No model.)

To all whom it may concern:

Be it known that I, CHARLES M. KIMBALL, of Toledo, in the county of Lucas and State of Ohio, have invented certain new and useful 5 Improvements in Bottle or Egg Carriers, of which the following is a specification.

This invention relates to that class of flexible packing or carrying devices which are composed of slats or strips of flexible material 10 interlocked or interlaced to form a structure comprising a number of cells or receptacles presenting flexible supports to bottles or other fragile articles intended to be supported and protected.

15 The invention consists in the improved construction which I will now proceed to describe, the same having for its object to provide a carrier which will be efficient for the purpose for which it is intended when it is in its operative position, and can also be readily folded into compact form for storage or shipment.

Of the accompanying drawings, forming a part of this specification,—Figure 1 represents a side elevation of my improved carrier 25 in condition for use. Fig. 2 represents a top plan view of the same. Fig. 3 represents a side elevation showing the strips which form the bottoms of the bottle receptacles turned upwardly to permit the folding of the carrier.

30 Fig. 4 represents a top view showing the carrier folded. Fig. 5 represents a perspective view showing a part of the carrier in its operative position. Figs. 6, 7, and 8 represent views of the parts of the carrier, detached.

35 The same letters of reference indicate the same parts in all the figures.

In the drawings—*a* represent a series of strips or partitions which may be made of suitably stiff pasteboard or other analogous 40 material, and are arranged at suitable distances apart to permit the insertion of the bottles or other articles to be carried, between said strips.

b represent narrower strips, which are arranged at right angles with the strips *a* when the device is in its operative position, and are arranged in pairs, as shown in Fig. 5, the arrangement being such that two strips *a* and four strips *b* constitute one cell for the reception of a bottle or other fragile article.

The strips *a* are provided with slots *c c* separated by tongues *c'*, which tongues are integral with the strips *a*, each tongue being free at one end to be bent outwardly and thus permit the insertion of a strip *b* in the slots *c c*. 55 Each strip *b* has a series of orifices *d* formed to receive the tongues *c'* so that after a strip has been inserted in the slots *c c* and moved to position, which will bring its orifices *d* into said slots, the strips *a* and *b* may be engaged 60 by forcing the tongues *c'* to their normal positions, the tongues passing through the orifices *d* and again separating the slots *c c*, as shown in Fig. 5. When the strips *b* are thus engaged with the strips *a*, the joints formed 65 by the tongues *c'* and orifices *d* constitute hinges which permit the ready folding or collapsing of the strips into the condition shown in Fig. 4, so that the carrier may be compactly folded for shipment or storage. 70

In the lower portions of the strips *a* are formed triangular or segmental orifices *e*, each having a substantially vertical side *e'* and a substantially horizontal side *e''*.

f f represent a series of bottom strips, which 75 pass through the orifices *e* and are provided with notches *f' f'* which are engaged with the strips *a* in such manner as to prevent endwise movement of the bottom strips.

The bottom strips *f* are formed so that they 80 can rest horizontally upon the horizontal edges *e''* of the orifices *e* when the device is in its operative position, said strips then forming the bottoms of the cells, the sides whereof are formed by the strips *a* and *b*. When the bottom strips are in the last described position, they prevent the folding of the carrier, so that before the carrier can be folded it is necessary to turn the strips upwardly against the vertical edges *e'* of the orifices *e*, as shown in 90 Fig. 3. When this is done, the device may be readily folded, as shown in Fig. 4.

It will be seen that the above described construction provides a carrier having a number of cells, each of which is provided with a flexible bottom strip supporting the weight of the article inserted in the cell, the construction being such that said bottom strip may be readily displaced to permit the compact folding of the carrier. 95

While I have designed the improved carrier principally for bottles, I do not limit myself to this use, and may use it for holding eggs or other fragile articles.

5 When the device is in use, it is inserted in a suitable box or case in the usual way:

I claim—

A bottle or egg carrier composed of the main strips *a* having orifices, the transverse strips *b* jointed to the main strips, and the adjustable bottom strips inserted in said orifices and

adapted to stand horizontally therein, to form bottoms of the cells; and to stand vertically and permit the folding of the carrier.

In testimony whereof I have signed my 15 name to this specification, in the presence of two subscribing witnesses, this 29th day of June, A. D. 1894.

CHARLES M. KIMBALL.
